UNITED STATES PATENT OFFICE.

CHESTER C. FIFIELD, OF DES MOINES, IOWA.

OIL RETAINER FOR VALVE TAPPETS.

Application filed August 30, 1927. Serial No. 216,423.

The object of my invention is to provide simple, durable and inexpensive means which may be applied to the tappet support of an internal combustion engine of that type employing an overhead valve, whereby leakage of oil around the tappets may be prevented without packing the valve rods.

A further object is to provide an oil retainer in the nature of an attachment which may be easily and quickly applied to the tappet support of internal combustion engines for the purpose of preventing the escape of oil around the upper ends of the tappet rods, and to provide in connection therewith means for easily and quickly clamping said attachment in position.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of the upper end of the valve casing of an engine and the lower ends of the cylinders, showing the manner in which my improved oil retainer is applied to the top of the valve chamber, and the manner in which the attachment is secured thereto.

Figure 2 is a detail sectional view taken on the line 2—2 of Figure 1.

Figure 3 is a perspective view of the clamp for securing the oil retainer in position.

Figure 4 is an inverted perspective view of one of the oil retainers, one end being shown in section.

Figure 5 is a sectional view of a slightly modified form of an oil retainer which may be built permanently into the engine.

The numeral 10 indicates a cylinder block of an internal combustion engine, and 11 the valve casings. The top of the valve casing is provided with what I shall term a tappet support 12. The said tappet support is designed to cover the cam shaft chamber 13 in which is mounted the cam shaft 14 having a cam 15. The tappet support is provided with a series of bushing openings 16, each of which is provided with a slidably mounted tappet rod 17. The upper ends of the rods 17 extend a slight distance above the tappet support. Each tappet rod 17 is designed to support and actuate a valve rod 18 which is caused to reciprocate vertically by the rotation of the shaft 14 and the action of the cam

15 on the tappet head 19 secured to the lower end of the shaft 17.

Oil is usually splashed into the chamber 13 to provide means for lubricating the bearings of the shaft 14, as well as the tappet shafts 17. The reciprocation of the tappet shafts 17 causes a certain amount of oil to work upwardly through the opening 16, which accumulates on top of the tappet support 12 and eventually runs down the side of the valve casing and is wasted.

I have overcome this difficulty by providing an upright circular wall or shell 20 around the upper end of each of the shafts 17, so that a cylindrical space or opening 21 is provided of a considerably larger diameter than the upper end of the shaft 17. The walls 20 are of a height somewhat greater than the upper end of the shaft 17 when moved to its upper limit of movement. The walls 20 are provided with a plate 22 which serves as a cover to keep out dirt and foreign matter. Said plate 22 has an opening 23 through which the valve rod 18 is slidably mounted, the opening being of slightly greater diameter than the rod to prevent friction, and permit free movement of the rod. The cover 22 may be detachably supported by means of suitable screws or cap bolts 24.

By this arrangement it will be seen that any excess oil which may move upwardly through the opening 16 will collect in the chamber 21 and run back through said opening each time the engine is stopped, so that in actual operation no oil is wasted.

For applying my invention to engines that are already in use, I have provided blocks 25, each of which is substantially rectangular in cross section and of a width substantially equal to the width of the walls 20 and of a height substantially equal to the height of said walls. Each of the blocks has its under surface provided with vertically extending openings 26 of a diameter equal to the spaces 21. The top of each of the openings 26 is provided with valve rod openings 27. Each of the openings 26 is provided with a sleeve 28 having its lower end extended beyond the under surface of the block 25 and designed to enter grooves 29 surrounding the upper end of the valve opening 16, said grooves being formed by a special tool. The blocks 25 are then inverted and placed in position with the lower ends of the sleeves 28 extended downwardly into the grooves 29. A packing 30 is pro-

vided for making a tight fit between the block 25 and the support 12, while the sleeves 28 hold the packing in position and the block 25 in proper alignment with the tappet shafts 17.

5 The valve rods 18 are mounted in the openings 27.

For clamping the blocks 25 in position without having to drill or tap holes in the support 12, I have provided a yoke 31 which

10 consists of a horizontal bar 32 having inwardly extending end portions 33 terminating in downwardly extending portions 34. The members 34 are designed to be mounted between the blocks 25 and the cylinder block 10.

15 A rod 36 is mounted between the blocks 10 and in the central portion of the bar 32. One end of the rod 36 is mounted in clamping plate 37 which rests against the back side of the cylinder blocks 10. A suitable nut 38 is pro-

20 vided for the forward end of the rod 36 and provides means whereby the member 34 may be drawn tightly against the blocks 10. The inner ends of the members 33 rest under the water jacket portion of the cylinder blocks in

25 the manner clearly illustrated in Figure 2. Each of the portions 33 is provided with a screw threaded opening 39 for receiving set screws 40, which rest on the center of the blocks 25 in the manner clearly illustrated in

30 Figure 1. Said set screws exert downward pressure on the blocks 25 and securely retain them in position. By this arrangement it will be seen that the blocks 25 may be easily and quickly attached or removed as desired

35 by loosening the set screws 40 and the nuts 38 and removing the rod 36.

The openings 26 of the blocks 25 are greater than the diameter of the tappets 17 and serve the same purpose as the spaces 21 of the form 40 illustrated in Figure 5, and operate in the same manner to prevent leakage of oil around the tappet shafts.

45 Thus it will be seen that I have provided a device of simple, durable and inexpensive construction, which may be either built permanently into the tappet support, or in the form of an attachment which may be connected to the engine after it has been built, and when so provided will prevent any leakage of oil working upwardly through the tappet bearings.

55 Other modifications of my device may be provided without departing from the spirit of my invention. The important feature is to provide in communication with the upper end of the tappet bearing opening a chamber or compartment larger than the upper end of the valve tappet in which the valve tappet may reciprocate so that oil will not collect by capillary attraction or otherwise, and to provide a suitable covering for said enlarged portion to exclude foreign matter, and to provide in the covering a suitable opening in alignment with the valve tappet for loosely 60 receiving the valve operating rods. The

parts are so arranged that the upper ends of the tappets never engage either the top or side walls of the enlarged opening.

It will readily be seen that if the upper ends of the tappets 17 extended upwardly 70 through the cover member and operated in a loosely fitting hole, oil would then adhere to the surface of the upper end of the tappet rod and be worked through the said opening in the same manner as it is worked through the 75 bearing opening 16. I find in actual practice that comparatively no oil creeps on the lower ends of the valve rods 18 on account of the valve rods being of considerably less diameter than the tappets, and further on account of 80 the upper ends of the tappets extending at all times above the level of any oil which might collect in the space 21.

On account of the valve rods 18 operating loosely in the openings 23 and 27, no lubrication is required for the rods at this point. On account of the small diameter of said rods, the space between the rods and the opening 23 is comparatively small, whereas if the upper ends of the tappets 17 were extended 90 through the cover 22 and allowed to move freely through the openings in said cover, the open space around said rods would be of considerable size and permit an excessive amount of dust and dirt to enter. For this reason it 95 will be seen that a further advantage is gained by retaining the upper ends of the tappets 17 below the cover plates of the enlarged chambers.

I claim as my invention:

1. In a device of the class described, a tappet support having a vertically arranged bearing opening terminating in an enlarged portion at its upper end, and a cover for the enlarged portion of said opening provided with a valve rod opening in alignment with said bearing opening, the enlarged opening being of such size that it will not become filled with oil by capillary attraction.

2. In a device of the class described, a tappet support having a vertically arranged bearing opening terminating in an enlarged portion at its upper end, a cover for the enlarged portion of said opening provided with a valve rod opening in alignment with said bearing opening, a tappet rod in said bearing opening, and a valve rod in the opening of said cover and supported in operative relation with said tappet rod, the parts being so proportioned and arranged that a space is 105 provided around the upper end of each of the tappets and of such size that it will not become filled with oil by capillary attraction, and the enlarged portion being of such height that the tappets may be reciprocated without engaging the cover of said enlarged portion.

3. An oil retainer for valve tappets comprising a block designed to be supported on the upper surface of a tappet support and having an opening in its under surface for 110

5 receiving the upper end of a tappet, said opening being larger than the upper end of the tappet and of such size that it will not become filled with oil by capillary attraction, and said block being provided with a valve rod

10 opening.
4. An oil retainer for valve tappets comprising a block designed to be supported on the upper surface of a tappet support and having an opening in its under surface for receiving the upper end of a tappet, said opening being larger than the upper end of the tappet and of such size that it will not become filled with oil by capillary attraction, said 15 block being provided with a valve rod opening, and a packing supported between said block and said tappet support.

20 5. An oil retainer for valve tappets comprising a block designed to be supported on the upper surface of a tappet support and having an opening in its under surface for receiving the upper end of a tappet, said opening being larger than the upper end of the tappet and of such size that it will not become 25 filled with oil by capillary attraction, said block being provided with a valve rod opening, a packing supported between said block and said tappet support, and means for clamping said block in position on said tappet support.

30 6. An oil retainer for valve tappets comprising a block designed to be supported on the upper surface of a tappet support and

35 having an opening in its under surface for receiving the upper end of a tappet, said opening being larger than the upper end of the tappet, said block being provided with a valve rod opening, a packing supported between said block and said tappet support, and means for clamping said block in position on said 40 tappet support, said means comprising a yoke having inwardly extending members designed to engage the inner faces of the cylinder block at a point adjacent to the tappet support, a rod and a clamping plate for securing said yoke in position.

45 7. In combination, an internal combustion engine comprising a cylinder block having a cam shaft chamber and a tappet support covering the same, said tappet support being 50 provided with vertical tappet bushings, a tappet shaft for each of said bearings having its upper end extended above said support, an oil retainer block having in its under surface a series of openings for receiving the upper ends of said tappet shafts when the block is placed in position on said support, the openings being of a diameter greater than the tappet shafts and of a height greater than the stroke of said shafts, a valve rod opening 55 communicating with said enlarged openings, and means for clamping said blocks in position on said support.

Des Moines, Iowa, August 23, 1927.
